Donald L. Kalish
ATTORNEY.

UNITED STATES PATENT OFFICE

WILLIAM SHULIK, OF PHILADELPHIA, PENNSYLVANIA, ASSIGNOR OF ONE-THIRD TO ABRAHAM KOUFMAN, AND ONE-THIRD TO ARTHUR S. LICHTEN, BOTH OF PHILADELPHIA, PENNSYLVANIA

FLEXIBLE SLIDE FASTENER

Application filed September 22, 1931, Serial No. 564,315. Renewed May 11, 1932.

My invention relates to flexible slide fasteners, and it relates more particularly to a new and improved slide for the same.

An object of my invention is to provide a slide having an easier movement, a more durable, and a less bulky construction.

Another object of my invention is to provide a slide having an improved and novel locking means whereby the slide may be fixedly engaged with the interlocked scoops or links when the slide is at rest.

A further object of my invention is to provide a slide for fasteners of the character stated, which will not only permit the operating tab or handle member to lie flat and within the plane of one of the wings of the body of the slide, but it will also leave the top or outer wing of the body of the slide clear and unobstructed by any handle member or projections or indentations or structural elements, so that the outer wing member of the body of the slide may present a clear and unobstructed panel which may be utilized for ornamentations of various kinds.

Thus, it is an object of my invention to form a slide for fasteners of the character stated in which all the functional elements of slide and handle are so arranged and related as to leave both the outer wing member of the slide as well as the operating handle member entirely clear and subject to ornamentation.

With the above and other objects in view, my invention consists of a flexible slide fastener, including a slide having an upper and a lower wing, grooves on the inner surfaces of said wings forming a central passageway therebetween, and two divergent passageways extending therefrom, to accommodate a row of interlocked scoops and each of two disengaged rows of scoops respectively; an upright portion joining the upper and the lower wings; a finger tab pivoted about the sides of the upper wing in a manner to permit said tab to lie in the same plane as said upper wing, when said tab is not being operated and is in a downward position; and a locking-pin projecting from the under surface of the finger tab, adapted to engage

between the interlocked scoops when the finger tab is in said downward position.

For the purpose of illustrating my invention, I have shown in the accompanying drawing forms thereof which are at present preferred by me, since the same have been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring to the drawing in which like reference characters indicate like parts:

Figure 1 represents a plan view of a slide fastener embodying my invention.

Figure 2 represents a side view of a slide fastener embodying my invention.

Figure 3 represents a plan view of a slide fastener of modified construction embodying my invention.

Figure 4 represents a side view of the same.

Figure 5 represents a sectional view taken on line 5—5 of Figure 4.

Figure 6 represents a sectional view taken on line 6—6 of Figure 3.

According to my invention, I provide two rows of scoops 6 and 7 joined and interlocked, as at 8, by means of a slide 9. The slide 9 is preferably pressed out of a single piece of metal so as to form an upper wing 10, a lower wing 11, and an upright wing-retaining spacer member 12.

A central groove 13, forked at 14 into two smaller divergent grooves 15 and 16 respectively, is pressed out of the interior face of each wing, so as to accommodate therebetween and therein a row of interlocked scoops and two rows of disengaged scoops, respectively;—the rows of scoops disengaging each other about the upright spacer member 12.

The upper wing 10 is slightly thickened at each of two opposite side portions 18 and 19 respectively and suitable opposite and axially aligned journal openings are provided to accommodate two opposed and axially aligned trunnions 20 and 21 projecting inwardly from the two leg portions 22 and 23 respectively of

85

100

the finger tap 17. The leg portions 22 and 23 are long enough to permit the finger tap 17 to swing clear of the end of the upper wing nearest the interlocked scoops, and to permit the 5 finger tab to lie in the same plane as the upper wing.

A locking-pin 24 projects from a point along the centerline of the finger tab 17 on the face nearest the interlocked scoops.

10 The finger tab 17, the legs 22 and 23, and the trunnions 20 and 21 are preferably formed integrally and pressed out of one piece of metal, the trunnions being sprung or pressed into the journal openings in the sides of the 15 upper wing 10.

I may also provide a pair of opposed detents 25 on the inner faces of the legs 22 and 23; said detents 25 being adapted to press against the sides of the upper wing 10 when 20 the finger tab 17 is swung into the locking position, thereby frictionally to retain said finger tab in the locking position. I may provide also, a pair of opposed notches 26 on the side of the upper wing, and so disposed there- 25 in as to receive the detents 25 when the finger tab 17 is swung into the locking position, tending more securely to lock said finger tab in said locking position. (See Fig. 6).

In use, the slide is drawn over the scoops 30 by means of the finger tab, which may be swung through a wide arc about the trunnions 20 and 21. When the slide is in its desired position along the scoops, the finger tab is pressed against the interlocked scoops, as 35 shown in Figure 2, thereby forcing the locking-pin 24 between the engaged scoops operatively to lock the slide against the same.

In Figures 3, 4 and 5 modified embodiments 40 of my invention are shown, illustrating the manner in which the exterior shape of the slide may be varied; Figure 5 being a section- al view.

It will thus be seen that by my invention, I 45 am enabled to unite the handle member and the body of the slide without any projections or obstructions on the face of the slide and so that the handle member might also lie in the plane of one of the wings of the slide, when not in use.

50 Further by means of my invention, the locking of the slide is assured whenever the finger tab is thrown into the inoperative position, there being but one position in which the finger tab is "out of the way", namely the lock- 55 ing position.

I am aware that the invention may be embodied in other specific forms without departing from the spirit or essential attributes thereof, and I therefore desire the present embodiment to be considered in all respects as 60 illustrative and not restrictive, reference being had to the appended claims rather than to the foregoing description to indicate the scope of the invention.

65 Having thus described my invention, what

I hereby claim as new and desire to secure by Letters Patent, is:

1. A flexible slide fastener including two interlocking rows of scoops, a slide having an upper wing and a lower wing and a trans- 70 verse spacer member joining the two wings, grooves on the inner surfaces of said wings, forming therebetween a central passageway, and two divergent passageways extending therefrom, to accommodate a row of interlocked scoops and each of two disengaged rows of scoops respectively, a finger tab having legs extending therefrom, the free ends of said legs being pivoted about the sides of the upper wing, said legs being long enough 80 to permit the finger tab to be swung into the same plane as the upper wing on the side nearest the interlocked scoops; and a locking-pin projecting from the face of said finger tab on the side nearest the interlocked scoops when said tab is in said position in the plane of said upper wing. 85

2. A flexible slide fastener including two interlocking rows of scoops, a slide having an upper wing and a lower wing and a trans- 90 verse spacer member joining the two wings, grooves on the inner surfaces of said wings, forming therebetween a central passageway, and two divergent passageways extending therefrom, to accommodate a row of interlocked scoops and each of two disengaged rows of scoops respectively; a finger tab having legs extending therefrom, the free ends of said legs being pivoted about the sides of the upper wing, said legs being long enough 95 to permit the finger tab to be swung into the same plane as the upper wing, and the outer face of said upper wing being free of functional projections and indentations. 100

3. A flexible slide fastener including two interlocking rows of scoops, a slide having an upper wing and a lower wing and a trans- 105 verse spacer member joining the two wings, grooves on the inner surfaces of said wings, forming therebetween a central passageway, and two divergent passageways extending therefrom, to accommodate a row of interlocked scoops and each of two disengaged rows of scoops respectively, a finger tab having legs extending therefrom, the free ends of said legs being pivoted about the sides of the upper wing, said legs being long enough 110 to permit the finger tab to be swung into the same plane as the upper wing on the side nearest the interlocked scoops; a locking-pin 115 projecting from the face of said finger tab on the side nearest the interlocked scoops when said tab is in said position in the plane of said upper wing, and means to retain said finger tab in the scoop-locking position. 120

4. A flexible slide fastener including two interlocking rows of scoops, a slide having an upper wing and a lower wing and a trans- 125 verse spacer member joining the two wings, grooves on the inner surfaces of said wings,

- forming therebetween a central passageway, and two divergent passageways extending therefrom, to accommodate a row of interlocked scoops and each of two disengaged 5 rows of scoops respectively; a finger tab having legs extending therefrom, the free ends of said legs being pivoted about the sides of the upper wing, said legs being long enough to permit the finger tab to be swung substantially into the plane of the upper wing. 10

5. A flexible slide fastener including two interlocking rows of scoops, a slide having an upper wing and a lower wing and a transverse spacer member joining the two wings, 15 grooves on the inner surfaces of said wings, forming therebetween a central passageway, and two divergent passageways extending therefrom, to accommodate a row of interlocked scoops and each of two disengaged 20 rows of scoops respectively, a finger tab pivoted about the sides of the upper wing in a manner to permit the finger tab to be swung into the same plane as the upper wing on the side nearest the interlocked scoops; and a 25 locking-pin projecting from the face of said finger tab on the side nearest the interlocked scoops when said tab is in said position in the plane of said upper wing. 30

6. A flexible slide fastener including two interlocking rows of scoops, a slide having an upper wing and a lower wing and a transverse spacer member joining the two wings, 35 grooves on the inner surfaces of said wings, forming therebetween a central passageway, and two divergent passageways extending therefrom, to accommodate a row of interlocked scoops and each of two disengaged 40 rows of scoops respectively; a finger tab pivoted about the sides of the upper wing in a manner to permit the finger tab to be swung into the same plane as the upper wing, and the outer face of said upper wing being free of functional projections and indentations. 45

7. A flexible slide fastener including two interlocking rows of scoops, a slide having an upper wing and a lower wing and a transverse spacer member joining the two wings, 50 grooves on the inner surfaces of said wings, forming therebetween a central passageway, and two divergent passageways extending therefrom, to accommodate a row of interlocked scoops and each of two disengaged 55 rows of scoops respectively, a finger tab pivoted about the sides of the upper wing in a manner to permit the finger tab to be swung into the same plane as the upper wing on the side nearest the interlocked scoops; a locking-pin projecting from the face of said finger tab on the side nearest the interlocked scoops when said tab is in said position in the plane of said upper wing, and means to retain said finger tab in the scoop-locking position. 60

8. A flexible slide fastener including two interlocking rows of scoops, a slide having an upper wing and a lower wing and a trans- 65

verse spacer member joining the two wings, 70 grooves on the inner surfaces of said wings, forming therebetween a central passageway, and two divergent passageways extending therefrom, to accommodate a row of interlocked scoops and each of two disengaged 75 rows of scoops respectively; a finger tab pivoted about the sides of the upper wing in a manner to permit the finger tab to be swung substantially into the plane of the upper wing. 80

9. A flexible slide fastener including two interlocking rows of scoops, a slide having an upper wing and a lower wing and a trans- 85

verse spacer member joining the two wings, 85 grooves on the inner surfaces of said wings, forming therebetween a central passageway, and two divergent passageways extending therefrom, to accommodate a row of interlocked scoops and each of two disengaged 90 rows of scoops respectively, a finger tab having legs extending therefrom, the free ends of said legs being pivoted about the sides of the upper wing in a manner to permit the finger tab to be swung into the same plane as the upper wing on the side nearest the interlocked scoops; and a locking-pin projecting from the face of said finger tab on the side 95 nearest the interlocked scoops when said tab is in said position in the plane of said upper wing. 100

10. A flexible slide fastener including two interlocking rows of scoops, a slide having an upper wing and a lower wing and a trans- 105

verse spacer member joining the two wings, 105 grooves on the inner surfaces of said wings, forming therebetween a central passageway, and two divergent passageways extending therefrom, to accommodate a row of interlocked scoops and each of two disengaged 110 rows of scoops respectively; a finger tab having legs extending therefrom, the free ends of said legs being pivoted about the sides of the upper wing in a manner to permit the finger tab to be swung into the same plane as the upper wing, and the outer face of said upper wing being free of functional projections and indentations. 115

11. A flexible slide fastener including two interlocking rows of scoops, a slide having an upper wing and a lower wing and a trans- 120

verse spacer member joining the two wings, 120 grooves on the inner surfaces of said wings, forming therebetween a central passageway, and two divergent passageways extending therefrom, to accommodate a row of interlocked scoops and each of two disengaged 125 rows of scoops respectively, a finger tab having legs extending therefrom, the free ends of said legs being pivoted about the sides of the upper wing in a manner to permit the finger tab to be swung into the same plane as the upper wing on the side nearest the interlocked scoops; a locking-pin projecting from the face of said finger tab on the side nearest the 130

- interlocked scoops when said tab is in said position in the plane of said upper wing, and means to retain said finger tab in the scoop-locking position.
- 5 12. A flexible slide fastener including two interlocking rows of scoops, a slide having an upper wing and a lower wing and a transverse spacer member joining the two wings, grooves on the inner surfaces of said wings,
- 10 forming therebetween a central passageway, and two divergent passageways extending therefrom, to accommodate a row of interlocked scoops and each of two disengaged rows of scoops respectively; a finger tab having legs extending therefrom, the free ends of said legs being pivoted about the sides of the upper wing in a manner to permit the finger tab to be swung substantially into the plane of the upper wing.
- 15 13. A flexible slide fastener including two interlocking rows of scoops, a slide having an upper wing and a lower wing and a transverse spacer member joining the two wings, a plurality of bearing apertures in the sides
- 20 of said upper wing; grooves on the inner surfaces of said wings, forming therebetween a central passageway, and two divergent passageways extending therefrom to accommodate a row of interlocked scoops and each of
- 25 two disengaged rows of scoops respectively; a finger tab having legs extending therefrom, trunnions extending from the free ends of said legs and adapted to be journalled in said upper-wing bearing apertures operatively to
- 30 pivot said finger tab about said upper wing in a manner to enable said finger tab to be swung into the same plane as said upper wing on the side nearest the interlocked scoops; and a locking-pin projecting from the face of
- 35 40 said finger tab on the side nearest the interlocked scoops when said tab is in said position in the plane of said upper wing.
14. A flexible slide fastener including two interlocking rows of scoops, a slide having an
- 45 upper wing and a lower wing and a transverse spacer member joining the two wings, a plurality of bearing apertures in the sides of said upper wing; grooves on the inner surfaces of said wings, forming therebetween a
- 50 central passageway, and two divergent passageways extending therefrom, to accommodate a row of interlocked scoops and each of two disengaged rows of scoops respectively; a finger tab having legs extending therefrom,
- 55 trunnions extending from the free ends of said legs and adapted to be journalled in said upper-wing bearing apertures operatively to pivot said finger tab about said upper wing in a manner to enable said finger tab to be
- 60 swung into the same plane as said upper wing.

In testimony whereof I have hereunto set my hand.

WILLIAM SHULIK.
